YARN BUNCHING MOTION FOR USE IN
RING SPINNING AND RING DOUBLING
FRAMESSamuel Bowler, Accrington, England, assignor
to Howard & Bullough Limited, Accrington,
EnglandApplication July 16, 1932, Serial No. 622,848,
and in Great Britain September 19, 1931

3 Claims. (Cl. 242—43.7)

The invention relates to ring spinning and ring doubling frames, and has for object the providing of a bunching motion therefor of an improved character, which is suitably automatic in action, and of a convenient and effective nature.

According to my invention, I provide an eccentrically or cam shaped scroll, mounted in revoluble manner away from or for operation independently of the usual doffing lever.

10 This scroll, when driven, through intervening mechanism gives a movement to the usual doffing quadrant of the frame, which movement results in a traverse of limited extent being imparted to the ring rail carrying the mounted rings.

15 As is understood, this quadrant is kept stationary during those periods when the spun yarn is being built up about the spindles, or about the pirns, tubes, or other like carriers. But said quadrant is moved upon an axis to allow of the 20 pirns or the like aforesaid being subsequently doffed or removed.

25 In the present invention, movement of the quadrant is made use of so that a reduced traverse of the ring rails involved may result in the formation of a bunch of yarn at the base part of each pirn or the like, prior to the ordinary building-up operation already mentioned. This bunch of yarn is put on a pirn, for example, to form a reverse supply for the use in automatic looms for 30 weaving.

According to my invention, the intervening mechanism between the driven scroll named and the quadrant moved thereby includes a piece, termed a finger-piece, in engagement with the 35 grooves of said scroll during bunching operations, which finger-piece through further mechanism operates a handle or pivoted lever, the movement of this handle causing the usual pinion in gear with the said doffing quadrant to be revolved in alternating manner for the purpose in view.

40 Means are employed for throwing out of gear the usual gearing for revolving the ordinary heart-shaped cam which normally controls the movement of the doffing lever used in building-up motions. And means are also employed for automatically, or otherwise, re-engaging said gearing when the bunching operation is completed.

50 The handle or pivoted lever by which the pinion named may be moved, is, according to my invention, capable of being moved into and out of the operative position by hand.

55 Referring to the accompanying drawings, Fig. 1 shows parts involved in my said invention

in relation to known portions of a ring spinning frame.

Fig. 2 is a detail of Fig. 1 and in plan.

Fig. 3 is a detached detail of Fig. 1 aforesaid, with parts in a changed position.

Fig. 4 is a plan view of another detail in Fig. 1, but included in Fig. 3.

Fig. 5 is a view at right angles to Fig. 1, other details being included, but with parts broken away.

Fig. 6 is a portion of Fig. 1 but with additional parts shown in Fig. 5 included.

Fig. 7 is a view at right angles to Fig. 5, and of an added detail therein.

The framing of the machine is shown in part 70 at 4. As is understood, the usual lifting levers for actuating the ring rail of the frame are operated by chain 8 shown in Fig. 1.

75 The chain 8 passes over a chain block 9 revolubly mounted on the doffing quadrant 10, which quadrant is pivoted in known manner upon the framing 4. The chain 8 is also connected to a further and known chain block, the latter being mounted concentric with the usual doffing lever. The last-named block is not indicated. As 80 understood the usual doffing lever 13, Fig. 5, is capable of an up-and-down movement brought about by means of a heart-shaped cam 14 bearing against a bowl 14^x mounted on said doffing lever. This bowl is shown below the cam 14 in 85 Fig. 5.

Motion is given to the cam 14 by means of bevel gearing shown at 15 (see Fig. 5). This gearing is operated by a helical gear 16 driven by a worm 17.

90 During a building-up operation the quadrant 10 is kept stationary by means of a stop 20 thereon being engaged by a catch 21 pivoted to the framing 4. But for doffing purposes, said catch is moved by hand into the disengaged position (Fig. 3) and the quadrant 10 is then capable of being lowered in manner well known, by the operation of a handle.

95 The movement of the quadrant slackens the chain 8, allows the ring rail to be lowered and 100 the doffing lever 13 to fall away from the cam 14, as is understood.

105 Before a new building up of yarn upon the carrier is commenced, a bunch of yarn has to be formed. For this purpose, and according to my present invention, I provide an eccentrically or cam shaped scroll 25 (Figs. 1 and 5) revolubly mounted in connection with the framing 4. This scroll is shown mounted away from or independently of the doffing lever 13. The scroll 110

named is driven by gearing such as at 26 (Fig. 5) in gear with wheel 27. This wheel 27 is fixed on the end of the front bottom roller and is driven through the usual well-known gearing from the 5 driving shaft of the machine.

A pivoted finger-piece 28 is capable of engaging the grooves of the scroll 25 by means of a projecting part at 29. This finger-piece is held in contact therewith by means of a spring 36 10 (Fig. 1) referred to later, so that the finger-piece may be disengaged by hand when necessary.

The piece 28 is pivoted at 28^x by passing between the sides of a slotted portion in part 31^x and connected by pin thereto, said part 31^x being 15 attached to a shaft 31 in manner indicated, which shaft is attached to a slotted arm 32, the latter being in connection by link 33 with a lever 34 pivoted at 35 on the frame 4. One end of the lever 34 is connected by the helical spring 36 20 already referred to, and only partly indicated in full, to the frame 4, while an opposite end mark 37 of the lever 34 is in link connection with a which lever replaces the ordinary handle employed 25 for moving the quadrant 10 as already referred to.

This lever 38 is slotted at the right-hand end in Fig. 1 in which slot is placed a flattened projection 39 which is pinned to the lever named, as indicated in Fig. 2. One end of a plate spring 38^x is shown attached to the projection 39, and which spring bears against the lever 38, (see also Fig. 2). The projection 39 is part of the shaft carrying the usual pinion now marked 40, and which is in gear with the teeth 24 of the quadrant 10, as already explained.

It will be obvious that under the conditions named and shown, when the lever 38 is moved outwardly on its pin attachment to the projection 39, as indicated by broken lines in Fig. 2 the pinion 40 can be partially revolved by the movement up-and-down of the lever 38, and in a direction vertically to the plane of Fig. 2. This movement, when the lever named is so positioned as 40 stated, may be utilized to ease the quadrant or slightly raise the same, when it is desired to disengage the catch 21 from the stop 20, for doffing purposes.

For the production of a bunch of yarn on each 50 yarn carrier, however, the lever 38 is capable of being moved into an aperture, here of flared form, at 41 provided in a link 42 connecting the said lever 38 with lever 34; (see full lines for lever 38 in Fig. 2).

When so connected, the lever 38 aforesaid becomes automatically under the control of the scroll 25, or the slight up-and-down movement of the lever 32, due to the action of the revolving scroll upon piece 28, will result in an alternating 60 and partial revolution of the pinion 40. This movement, through the quadrant 10, and chain 8 will give the small traverse of the ring rails necessary to form the bunch of yarn 2 before-named.

The conditions necessary for this bunching motion to be operating, require the disconnection of the heart-shaped cam 14, for which purpose, a clutch at 43 (Fig. 5) between gearing 17 and bevel 15 is capable of being disengaged by operation of a pivoted handle 44 in connection with the upper part of the clutch 43. The depression of the handle 44, in the example given, allows a drop-catch 45 to pass in front of a projection 46 70 on the handle 44. This catch 45 temporarily

holds the handle 44 in the depressed position named.

In this way, the heart-shaped cam 14 ceases to function during the bunching operation. For adjusting the cam 14 so that the bunch may be correctly positioned, on the yarn carrier, gearing 47 is movable by a handle 48 which moves round a cam 49 on the shaft 50 until a pawl 51 falls into gear with the cam illustrated (see Figs. 5 and 7). The pawl 51 is pivoted on the frame of the machine.

After a bunching operation is completed, and the ordinary building-up of the yarn on the yarn carrier is desired to be commenced, the clutch 43 may be automatically put into gear again, for which purpose, according to what is illustrated, the projecting end 37 of the lever 34 is arranged to press down a part 52 of the drop-catch 45 (Fig. 6 more particularly), and at an opposite side of a pivot 53 therefor. The part 52 is here a stud (with a squared end below) in screw thread connection with a part 45^x of the catch 45, the height of the upper end of 52 thus being adjustable. The part 45^x named is attached to a shaft 53^x (see Fig. 5) the latter being attached to the drop-catch 45. Contact between lever-end 37 and part or stop 52, tends to turn shaft 53^x and to turn the catch 45 about the pivot 53. Said catch 45 is thus lifted clear of the handle-projection 46 before-named, and the handle 44 is then able to lift, such as under the action of a spring 54 shown in Fig. 5.

The extra amount of depression on the part of the end 37 of lever 34, is attained by the scroll 25 being provided with an extended grooved part 55, so that when the finger-piece 28 is engaged by said extended part, it is pushed away from the axis of the scroll named to a greater extent than before. This increased movement gives the result already referred to.

It is obvious that the form of the scroll may be adapted to the needs involved, and that the intervening mechanism employed may be considerably altered or modified to suit the conditions under which the same is used.

A spring-resisted catch 56 (Figs. 1, 3 and 4) is shown pivoted at 57 to a bracket 58 attached to the frame 4, which bracket also supports pinion 40. For said spring resistance a plate spring 57^x is shown in Fig. 1 passing behind an upright part 56^x from a part of catch 56 projecting on the left of pivot 57. (See also Fig. 4.) This catch 56 operates to hold up the catch 21 in the position shown at Fig. 3 and when the handle or lever 38 is in the position shown by broken lines in Fig. 2 the quadrant 10 is then supported by the hand-control of lever 38 through pinion 40. That is to say, when so held, said quadrant is free of the catch 21, the latter having previously been moved into the inactive position shown in Fig. 3 and retained in that position by the catch 56.

But when the lever 38 is moved into engagement with the part 41 of link 42 (Figs. 1 and 2) said lever pushes against a stop 59 on the catch 56, and turns the latter on pivot 57 so that said catch 56 is disengaged from catch 21. The latter is then free to fall by gravity to the position shown in Fig. 1 ready for abutting against the stop 20 on the quadrant 10. In practice, the weighted and extended end 21^x of the catch 21 140 would come against a stop below it on part of the framing 4, to limit the extent of fall of the catch 21 aforesaid. This happens, as already inferred, when the bunching operation ceases.
